UNITED STATES PATENT OFFICE.

DWIGHT G. LYMAN, OF OMAHA, NEBRASKA.

CARRIER.

No. 841,260.

Specification of Letters Patent.

Patented Jan. 15, 1907.

Application filed August 17, 1905. Serial No. 274,604.

To all whom it may concern:

Be it known that I, DWIGHT G. LYMAN, a citizen of the United States, residing at Omaha, in the county of Douglas and State of Nebraska, have invented certain new and useful Improvements in Carriers, of which the following is a specification.

This invention relates to carriers for overhead and similar conveyers, and refers particularly to a means for holding the carrier at the point where the bucket is to be loaded.

The invention refers, further, to a means for automatically releasing said holding means when the bucket is hoisted.

The invention further refers to various other improvements in detail hereinafter more fully shown and described.

In the accompanying drawings, Figure 1 is a side elevation of a carrier embodying the features of my invention. Fig. 2 is a longitudinal vertical section taken through the carriage of said carrier. Fig. 3 is a similar view showing the parts in a different position. Fig. 4 is a transverse section through the carriage on the line of the hoisting-shaft. Fig. 5 is a front elevation of the bodily-sliding latch-bar for holding the hoisting-head to the carriage. Fig. 6 is a view of the locking-latch by means of which the carriage is retained in position during the operation of loading the bucket. Fig. 7 is an end elevation of the hoisting-head and the operating-head. Fig. 8 is a fragmental sectional view on the line of the pivotal shaft of the bucket.

In the embodiment herein shown and described of this invention I provide supporting-cables 1, suspended in the usual manner across the space over which it is desirable to transport material, stretching said cables reasonably taut, and supporting them so that the point at which the bucket takes its load is somewhat lower than the point to which the load is to be conveyed.

The hoisting-drum (not shown) is located near the point of deposit, so that the carrier runs by gravity to its loading position and is elevated and drawn to its dumping position by the hoisting-drum. The carrier comprises four hanger-arms in pairs 2 and 3, one pair being located at each end of a carriage-body composed of outer plates 4 and intermediate plates 5, with spacing-blocks 6 between said plates near the ends of the latter. A guide-wedge 6^a, to be hereinafter described, is fixed in position between the plates 5. The upper ends of the hanger-arms are rig-

idly connected by means of a brace-rod 6^b, while their lower ends are secured to the outer sides of the outer plates 4 by bolts passing through the carriage. The upper ends of the hanger-arms 2 and 3 lie near together, and between them sheaves 7 are mounted for running upon the supporting-cables 1 and suspending said carriage therefrom.

A shaft 8 extends transversely through suitable openings in the plates 4 and 5, bearing-bosses 9 being rigidly secured to the outer sides of said plates 4 to provide suitable bearings for the ends of said shaft. Intermediate its ends and in the spaces between the inner and outer plates I have mounted loosely upon said shaft sheaves 10 and 11, over which the hoisting-cable 12 is adapted to run. One end of said cable is secured to the carriage by means of a hook 13, and the other end running to the hoisting-drum passes from said carriage over the idler-sheave 14, rotatably mounted at the forward end of the carriage.

The outer plates 4 of the carriage-body extend somewhat above the inner plates 5 thereof, a cover-plate 15 being secured in position over the separating-blocks 6. Between said outer plates a locking-latch 16 is placed, said latch being pivotally mounted upon a bolt 17, lying in suitable openings in the hanger-arms 2. To the upper side of the latch is rigidly secured a bar 18, the ends of which bar extend into concentric openings 19 in said plates 4, said openings providing a means for limiting the extent of the pivotal movement of said locking-latch. Adjacent to the latch 16 and in the opposite end of the carriage 12 a yielding bar 20 is mounted, the ends of which bar project outwardly through elongated openings 21 in the plates 4. The bar 20 is held forward toward the center of the carriage by means of extension coiled springs 22, secured by suitable means to the outer plates 4 and to the ends of said bar. To the upper side of the bar 20 are secured two blocks 23.

The hoisting-head 24 is provided with a transverse shaft 25, supported in bearings in said head, and intermediate its ends has sheaves 26, loosely mounted on said shaft. The sheaves 26 are separated in the hoisting-head 24 by vertical plates 24^a 24^b, corresponding in position with the plates 4 and 5 of the carriage-body, and said sheaves 26 correspond in position with the similar sheaves 10 and 11 and coöperate with said sheaves to

- carry the hoisting-cable 12. Upon its opposite sides the hoisting-head 24 is provided with outwardly-extending ears 27, to which the carrying-chains 27^a for the bucket-sections are secured. A dog 28 is pivotally mounted within the hoisting-head between the intermediate plates 24^b thereof, a bolt 29, passing through suitable openings in said head, being the means of support for said dog. 5
- 10 The upper end of the dog 28 has a forwardly-extending operating-arm 30, which arm projects through the open forward end of the hoisting-head 24, between the inner plates 24^b thereof.
- 15 The bucket 31 is of the ordinary sectional or clam-shell construction, the sections being pivotally connected by means of a shaft 32, beneath which shaft said sections are suspended by means of the arms 33, the lower 20 ends of which arms are rigidly secured to the ends of the sections. The shaft 32 is square in cross-section save for the points upon which the arms 32 bear upon it. Near its middle portion said shaft carries an upwardly-extending guide and tripping-rod 35, said rod being pointed at its upper end and adapted to enter the openings between the inner plates 5 of the carriage-body and there engage the locking-latch 16, which operation 25 will be described more fully hereinafter.
- 30 The bucket-sections are moved into an open position by means of an operating-head 36, comprising transverse bars 37, through suitable openings, in which bars a bolt 38 extends, which bolt is adapted to be engaged by the dog 28 to hold said operating-head in position relative to the hoisting-head when the bucket is loaded. At their outer ends the bars 37 carry pivotal links 39, the opposite 35 ends of which links are pivotally connected with the closing-arms 40, which arms are fixed at their lower ends to the opposite sections of the bucket 31. Each section of the bucket is provided with a chain 41 at either 40 end, which chains connect with the chains 27^a, depending from the hoisting-head 24, and likewise with chains 42, connected to the shaft 32. The hoisting-head also has a rigid upwardly-extending locking-arm 43, the upper end of which is provided with a notch 44, which notch is adapted to be engaged by the yielding bar 20 in order to support the hoisting-head from the carriage in the position 45 shown in Fig. 1.
- 50 A stop-block 45 is adapted to be secured to the lower cable 1 by means of clamping-bolts 46, passing through the two side plates 47 of said stop-block. The block also has two upwardly-extending arms 48, between the upper ends of which a sheave 49 is supported, which said sheave is adapted to rest upon the upper cable 1. A hook 50 is mounted upon each side of the stop-block 45, the forward ends of said hooks projecting forwardly a distance from said stop-block. At their rear 55

ends the hooks 50 are pivotally mounted upon the stop 45 by means of a bolt 51, passing through suitable openings in said stop-block and hooks. Forwardly of said bolt 51 said hooks are held between two bolts 52, 7 passing through two of a series of openings 53 in the stop-block, in order to provide an adjustment for the forward end of said hooks. The hooks 50 are adapted to enter the upper portion of the carriage between the outer plates 4 thereof and there be engaged by the latch 16.

In practice the cableway is arranged so that the point at which the bucket is to be loaded is somewhat lower than the point to which the load is to be drawn in order that the bucket may be run by gravity to the loading-point. The hoisting-engine for raising and transporting the loaded bucket is located at the discharge end of the cableway. 80 The stop-block 45 is adjusted in position upon the cables 1 above the loading-point. As the carrier with the open bucket suspended therefrom upon the chains 27^a approaches said stop-block the locking-hooks 50 are 85 thrust into said carrier beneath the locking-latch 16. The forward ends of said locking-hooks pass beyond the free end of said locking-latch and engage the blocks 23 upon the yieldingly-mounted bar 20, pushing said bar 90 out of the notch 44 of the suspending arm 43 and permitting the hoisting-head 24, to which said suspending arm is attached, to drop as the cable 12 is paid out. When the open bucket settles upon the material to be removed, the hoisting-head in turn settles upon the operating-head 36, the hook 28 engaging the bolt 38 and locking said heads together. The hoisting-cable 12 is now wound upon the hoisting-drum and the hoisting-head raised 100 toward the carriage. As the hoisting-head approaches the carriage the unlocking-bar 35 is projected upward through said carriage until it disengages the locking-latch 16 from the hooks 50, and the locking-bar 43 in like 105 manner engages the locking-bar 20, locking the hoisting-head to the carriage and freeing the latter from the stop-block 45. The unlocking-bar 35 and the locking and suspending bar 43 are guided to their proper position 110 by the guide-wedge 6^a. Continued winding up of the cable 12 causes said carriage, with the loaded bucket, to travel up the incline to 115 the delivery-point, where the hook 28 is withdrawn from the bolt 38 to damp the bucket. 120

I claim as my invention—

1. In a carrier, in combination, a carriage; means for locking said carriage upon a way; a hoisting-head; a cable arranged to extend between said carriage and said hoisting-head; a bucket movably supported from said hoisting-head; a locking member on said carriage; a suspending member attached to said hoisting-head and adapted to engage said locking member; a member carried by said

ucket for operating said carriage-locking means; and a guide member in said carriage, said suspending member and said lock-operating member being arranged to pass at opposite sides of said member.

2. In a carrier, in combination, a carriage having guide-openings in its sides; a member adapted to be fixed with relation to the way upon which said carriage is adapted to travel; a hoisting-head having an operating cable connection with said carriage; a spring-actuated locking-bar slidably mounted in said carriage, the ends of said bar lying in said guide-openings; and a suspending member attached to said hoisting-head and adapted to engage said locking-bar, the member fixed to the carriage-way being adapted to move said locking-bar out of engagement with said suspending member.

3. In a carrier, in combination, a carriage; a locking-latch on said carriage; a member adapted to be fixed with relation to the way and to project into said carriage, said member having a hooked forward end adapted to engage said locking-latch; a hoisting-head movably supported from said carriage; a locking member on said carriage in the path of the relative movement of the member fixed to the way and arranged to be moved out of locking position by said fixed member; and a suspending member on said hoisting-head adapted to engage said locking member.

4. In a carrier, in combination, a carriage, a pivoted locking-latch on said carriage, a member adapted to be fixed with relation to the way and to project into said carriage, said member having a hooked forward end adapted to engage said locking-latch; a

hoisting-head movably supported from said carriage; a spring-pressed locking member 40 slidably mounted on said carriage in line with the member fixed to the way and arranged to be pushed out of locking position by said fixed member; and a suspending member on said hoisting-head adapted to engage said 45 slidably locking member.

5. In a carrier, in combination, a carriage; a hoisting-head movably supported from said carriage; a bucket movably supported from said hoisting-head; coöperating means on 50 said carriage and said hoisting-head for locking said carriage and hoisting-head together; a locking member on the carriage-way; a locking-latch on said carriage adapted to be engaged by said locking member, said member being adapted to release said hoisting-head; and a member moving with said bucket for disengaging said latch and locking member.

6. In a carrier, in combination, a carriage 60 comprising a plurality of spaced plates; a shaft rotatably supported in said carriage; two sheaves on said shaft between certain of said plates; a guide member between said sheaves; a hoisting-head provided with two 65 sheaves; a cable extending over said sheaves; a locking member on said carriage; and a suspending member on said hoisting-head adapted to extend into said carriage and be guided by said guide member into engagement with 70 said locking member.
